UNITED STATES PATENT OFFICE

THOMAS K. COX AND HENRY L. GASSETT, OF COLUMBUS, GEORGIA

SPINNING FRAME SADDLE

Application filed July 25, 1930. Serial No. 470,742.

The present invention relates to spinning machines or frames, and more particularly to the weight transmitting saddles for the top rolls of the machines.

5 An object of the present invention is to produce yarn of a more even size than is produced with present equipment; to reduce to a minimum frictional contact between the saddle and the rolls; to cause the front leather 10 roll to run smoother and thus prolong the life of the roll; to reduce power consumption in the operation of the spinning frame; and to provide a saddle, the wear on which is confined to parts which are readily replaced to 15 save the cost of replacement of the entire saddle.

With the foregoing and other objects in view, the invention will be more fully described hereinafter, and will be more particularly pointed out in the claim appended hereto.

In the drawings, wherein like symbols refer to like or corresponding parts throughout the several views,

25 Figure 1 is a longitudinal section taken through a roller set of a spinning machine or frame, and with a saddle constructed according to the present invention applied thereto.

30 Figure 2 is a fragmentary top plan view of the same.

Figure 3 is a detail perspective inverted view of the front saddle, and

Figure 4 is a detail perspective view of 35 the rear saddle.

Referring now to the drawings, Figures 1 and 2 show a roller set as used in a spinning machine or frame, and the set comprises a series of metal rollers 10, which are the bottom rollers, and against the upper sides of which bear the upper leather covered rollers 11. As shown in Figure 1, the pairs of rollers 10 and 11 are three in number, providing front and rear end pairs and an intermediate pair. The yarn is pulled through the pairs of rollers and in order to exert the desired pressure on the yarn, pressure is applied to the top rollers 11 so as to urge the same downwardly toward the bottom rollers 10 by a weight or the like.

According to the present invention, a saddle is employed. The saddle comprises a front saddle section and a rear saddle section. The rear saddle section is in the form of an elongated relatively flat bar 12 having 55 at its rear end, and at its underside, a concavity or recess 13 adapted to embrace the shaft or hub portion 14 of the rear top roll 11, as shown in Figure 1, to hold the rear saddle 12 against longitudinal shifting. The 60 front end of the rear saddle rests upon the upper side of the hub or shaft 14 of the intermediate top roll 11. The rear saddle 12 is provided with oil openings 15 extending downwardly therethrough, and opening 65 against the hubs or shaft sections 14 of the top rolls, against which the rear saddle rests. The openings 15 extend upwardly through the bottom of wells 16 adapted to receive grease, or other suitable lubricant, for supplying the same to the contact surfaces between the roll shafts 14 and the front and rear end portions of the rear saddle 12.

70 The rear saddle 12 is also provided, intermediate its ends, with an upwardly extending and rearwardly enlarged lug 17 for cooperation with the front saddle 18, as herein-after explained, to maintain the front and rear saddle sections in alignment with one another.

75 The front saddle section 18 comprises an elongated bar which may be offset downwardly at its rear end, and provided thereat and at its underside with a pair of spaced apart flanges 19 providing a guide adapted to 80 embrace the lug 17 for holding the lug slidably between the guides. At the offset, the bar 18 is provided with an oil receiving opening 20 which extends downwardly and leads not only to the lug 17, but also to the front lubricant well 16 for supplying oil or grease 85 thereto.

90 The forward end of the front saddle or bar 18 is forked to provide fork arms 21, between which are disposed spaced rollers 22 mounted on pins 23, which extend through the rollers and into the fork arms 21. The rollers 22 are so located as to project below the roller edges of the fork arms 21, and the latter are 95 suitably recessed to cooperate with the lower 100

adjacent sides of the rollers 22 in forming a cavity or rest between the rollers, so that the rollers may properly seat the spaced points upon the upper side of the shaft 14 of the upper front roll 11. The rollers 22 are adapted, therefore, to not only maintain the front saddle section 18 against longitudinal displacement, but to also reduce frictional contact between the front saddle and the 10 front high speed roller 11, and insure the smooth and even running of the roller without reducing the necessary pressure on the saddle to produce uniform yarn.

The front saddle 18 is provided with a 15 transverse slot 24 for the reception of a stirrup, or the like, by means of which the weight is connected to the saddle, and is also provided with a projection or shoulder 25 in suitable spaced relation rearwardly of the slot 20 24 for holding the stirrup from slipping.

It is thus apparent that with a saddle of this construction the rear and intermediate contacts between the shafts 14 and the ends of the rear saddle 12 are properly lubricated, 25 so as to offer the least possible resistance incident to direct contact, while the front saddle 18 is seated by means of its rollers 22 on the shaft 14 of the front roller 11 to reduce wear between the front saddle 18 and the 30 front roller as the latter is driven at a relatively high rate of speed as compared with the other rolls and, consequently, the desired pressure may be exerted through the rollers 22 to the roll 11 without proportionately increasing the frictional contact or resistance between the same.

When the rollers 22 are worn appreciably by continued and prolonged use, it is evident that these rollers 22 may be quickly and 40 easily replaced by new rollers merely by removing the pins 23, and again replacing them on new pins after such pins are worn. The entire saddle structure, therefore, need not be discarded upon the wear of the bearing 45 surface of the front end of the front saddle, such as has been the custom in the past. The saddles thus last indefinitely, and it is economical and easy to effect a replacement of the bearing rollers 22.

50 It is also apparent that the overlapping inner ends of the front and rear saddle sections are permitted easy and ready relatively sliding movements one upon the other, incident not only to the arrangement of the 55 lubricating opening 20, but also incident to the positions and the opposite flaring of the lug 17 and the flanges 19.

The weight may be imposed on the saddle by the stirrup or any other suitable device 60 adapted to engage across the upper surface of the front saddle 18 adjacent to the shoulder or projection 25, so that the pressure of the weight is transmitted directly upon the front roller 11, and is also transmitted and 65 divided between the intermediate and rear

top rollers 11 through the rear saddle section 12.

It will be obvious that various changes in the construction, combination and arrangement of parts could be made, which could be 70 used without departing from the spirit of our invention, and we do not mean to limit the invention to such details, except as particularly pointed out in the claim.

Having thus described our invention, what 75 we claim and desire to secure by Letters Patent of the United States is:—

A spinning frame saddle, comprising a rear section having lubricant wells in its upper side near its opposite ends and having 80 openings therethrough leading from the bottoms of the wells, said rear section also having in its under side a bearing depression in register with the adjacent lubricant opening to seat upon the rear top roll shaft and hold the front end of the section at its adjacent lubricant opening across the intermediate top roll shaft, said rear section further having a forwardly tapering lug on its upper face adjacent the forward well, a front section having a forked front end and provided at the under side of its rear end with a pair of rearwardly diverging flanges to embrace said forwardly tapering lug, said front section also having a lubricant opening through its rear end portion leading to the forward ends of the flanges to conduct a lubricant to the flanges and the lug and into said front well of the rear section.
